Primary Examiner—Celia Murphy(74) *Attorney, Agent, or Firm*—Finnegan Henderson Farabow Garrett & Dunner LLP(57) **CLAIM**

The ornamental design for the medical instrument container, as shown and described.

DESCRIPTION

FIG. 1 is a perspective view of an embodiment of the medical instrument container of my new design in a partially closed position;

FIG. 2 is the top view of the design of FIG. 1 in a completely open position;

FIG. 3 is the bottom view of the design of FIG. 1 in a completely open position;

FIG. 4 is the right side view of the design of FIG. 1 in a completely open position;

FIG. 5 is the front view of the design of FIG. 1 in a completely open position;

FIG. 6 is the left side view of the design of FIG. 1 in a completely open position; and,

FIG. 7 is the rear view of the design of FIG. 1 in a completely open position.
